UNITED STATES PATENT OFFICE

130,391

DESIGN FOR AN AIRPLANE

William K. Ebel, Kingsville, and Benjamin T. Salmon, Towson, Md., assignors to The Glenn L. Martin Company, Baltimore, Md.

Application December 6, 1940, Serial No. 97,108

Term of patent 14 years

To all whom it may concern:

Be it known that we, William K. Ebel and Benjamin T. Salmon, citizens of the United States and residents, respectively, of the city of Kingsville, in the county of Baltimore and State of Maryland, and of the city of Towson, in the county of Baltimore and State of Maryland, have invented a new, original, and ornamental Design for an Airplane, of which the following is a specification, reference being had to the accompanying drawings, forming part thereof.

Figure 1 is a perspective view of an airplane

embodying our new design, the landing gear being in retracted position,

Figure 2 is a side elevational view thereof,

Figure 3 is a top plan view thereof, and

Figure 4 is a front elevational view thereof, showing by dotted lines the landing gear in extended position.

We claim:

The ornamental design for an airplane, substantially as shown.

WILLIAM K. EBEL.
BENJAMIN T. SALMON.
